Inventor

George Patton,

By Clarence A. O'Brien
Attorney

UNITED STATES PATENT OFFICE.

GEORGE PATTON, OF BICKNELL, INDIANA.

MAGAZINE HAMMER.

Application filed August 8, 1927. Serial No. 211,508.

This invention relates to new and useful improvements in magazine hammers, and has for its primary object to provide a hammer of this type that is constructed with feeding and delivery mechanism for the 5 nails or tacks.

A further and important object contemplates the provision of means of such a nature as to feed successively the tacks or nails 10 to the delivery mechanism, which mechanism is manually operable to deliver the tacks or nails one at a time into final position against the head of the hammer.

Further, the invention contemplates the 15 provision of a magazine hammer, wherein the nails or tacks may be almost entirely driven into the work by holding the hammer in one position, and striking a blow 20 against the work, whereupon the shock of the blow releases the nail or tack from that particular end of the hammer head, after 25 which the tool may be inverted so that the opposite end of the head may be struck against the nail or tack to complete the driving operation.

The invention further aims to provide a magazine hammer which is of relatively simple construction, and inexpensive of manufacture, but yet highly efficient in operation, the device consisting but of few parts 30 so co-related as to reduce the possibility of disarrangement to a minimum.

With the foregoing and other objects in view as the nature of the invention will be 35 better understood, the same comprises the novel form, combination and arrangement of parts hereinafter more fully described, shown in the accompanying drawings and claimed.

40 In the drawings:

Figure 1 is a view mainly in longitudinal section of my improved magazine hammer, the feeding mechanism being disclosed in normal position to permit the tack that has 45 been fed to the end of the head, to be driven into the work.

Fig. 2 is a view mainly in side elevation but disclosing the major portion of the head in section, and disclosing the feeding mechanism in the position of feeding a nail or tack to a point projected from the end of the head so that the same may be driven.

Fig. 3 is a vertical section through the head of the hammer, taken substantially 55 upon the broken line 3-3 of Fig. 1, for more

clearly disclosing the means for retaining the projected nail or tack in position to permit the driving thereof.

Fig. 4 is a detail horizontal section taken substantially on the line 4-4 of Fig. 1 for 60 more clearly disclosing the construction of the feeding means.

Fig. 5 is a reduced bottom plan view of the entire hammer, and

Fig. 6 is a transverse section through the 65 hammer handle taken substantially upon the line 6-6 of Fig. 2.

Now having particular reference to the drawings, my novel magazine hammer consists of a handle 5 of suitable shape in cross 70 section, equipped at one end with a head 6 preferably formed integrally with said handle.

As clearly shown in Figs. 1, 2 and 3, this head 6 is constructed to provide at one end, 75 an enlarged circular portion 7, and at its other end with a smaller circular portion 8 the purpose of which will be hereinafter more fully described. The larger end 7 of the head 6 is provided with a longitudinally 80 extending slot 9 while the bottom surface of the enlarged end 7 of said head 6 intermediate the ends of said slot 9 is formed with a relatively large circular opening 10.

Slidable longitudinally within this slot 9 85 is a block 11 that is formed adjacent its forward end with a vertically extending circular opening 12 for a purpose hereinafter more fully described. The handle 5 is formed throughout its length with a horizontal circular bore 13, that merges into a curved bore 14, extending vertically through the head 6, the lower end thereof terminating at a point directly in registration with the opening 10 in the bottom surface of said 90 enlarged end 7 of the head 6, see Figs. 1 and 2.

Swivelly connected to the rear end of the handle 5 at the termination of the bore 13 therethrough, as at 15, is a flexible tube 16 100 of any predetermined length that has communication with a source of nail or tack supply, it being obvious that the nails or tacks, as indicated by the reference character A, in Figs. 1, 2, and 3, are arranged 105 within the bore point foremost while the heads of the nails or tacks are engaged by the points of the next succeeding nails or tacks, with the obvious result that as the same are forced into the bore 13, the pre- 110

ceding ones will be caused to travel forward-
ly to the bore 13, and the bore 14 in the han-
dle 5 and head 6 respectively.

5 Detachably secured to the bottom surface
of the handle 5 directly in back of the head
6, and longitudinally with respect to said
handle, is an elongated sleeve 17 open at its
inner end, as clearly disclosed in Fig. 1.
10 Slidable longitudinally through this sleeve
17 is a rod 18 that is extended through an
opening in the rear end of the sleeve, while
the forward end thereof is bent downward-
ly as at 19 and arranged at the end of this
15 downturned portion within a vertical bore
20 formed in the rear end of the previously
mentioned sliding block 11.

20 The rear end of this rod 18 is bent up-
wardly alongside of the handle 5 and is so
bent as to provide a thumb piece. The rod 19
25 at a point directly within the forward open
end of the sleeve 17 is provided with an
abutment 22, while arranged around the
rod between this abutment and the rear end
of the sleeve 17, is an expansible coiled
25 spring 23 for the purpose of normally mov-
ing the downturned end 19 of the rod 18, in
a forward direction for manifestly main-
taining the block 11 in forwardly slid posi-
tion, so that the vertical opening 12 will be
30 out of registry with the said bore 14 of
the opening 10 in the bottom wall of the en-
larged end 7 of said head, see Fig. 1.

35 However, when the thumb piece 21 of the
rod 18 is drawn rearwardly against the ac-
tion of the spring 23, said block 11 will be
drawn rearwardly to the position indicated
40 in Fig. 2, whereupon said opening 12 will
register with the bore 14 and opening 10, to
permit the nails or tacks to pass there-
through.

45 In order to maintain the foremost nail or
tack in projected but attached relation with
respect to the hammer head 6, the enlarged
end 7 at opposite sides of the block 11 are
50 provided with tapered slots 24-24, in the
upper ends of which are pivotally arranged,
depending arms 25-25 which are normally
maintained in relatively tight engagement
55 with the side walls of the block 11 by springs
26-26.

55 The lower ends of these arms 25-25 are
formed with inwardly extending and slight-
ly tapering fingers 27-27 for engagement
beneath the block 11 and for engagement
beneath the head of the particular nail or
60 tack that has been permitted to drop from
the opening 12 from the block 11 when the
same is moved from the position indicated in
Fig. 1, to that indicated in Fig. 2.

60 The thumb piece 12 is then released,
whereupon the block 11 will return to the
position indicated in Fig. 1, and thus afford
an impact block for the particular nail or
tack that has been projected. Obviously,
65 that particular nail or tack may be driven

into the work by the ordinary manipulation
of the hammer.

The tension of the springs 26-26 of the
arms 25-25 is so minor, that upon the en-
gagement of the head of the hammer with
70 the work, the shock thereof will cause the
said arms 25-25 to swing away from the
block 11 and consequently, the particular
nail or tack that has been driven, so that
the same will remain within the work. 75

This operation does not completely drive
the nail or tack into the work, but it is only
necessary to turn the handle over so that the
nail or tack may be given a further blow
by the solid end 8 of said head 6. 80

85 In view of the foregoing description, when
considered in connection with the accom-
panying drawings, it will therefore be seen
that I have provided a highly novel, simple,
and highly efficient type of magazine ham-
mer that is well adapted for all of the pur-
poses heretofore designated, and even though
I have herein shown and described the in-
vention as consisting of certain detail struc-
tural elements, it is nevertheless to be under-
90 stood that some changes may be made there-
in without affecting the spirit and scope of
the appended claims.

95 Having thus described my invention, what
I claim as new is:—

1. In a magazine hammer of the charac-
ter described, a handle, a head arranged
upon one end of the handle, a short slot in
one end of the head, a block slidable within
said slot, said handle and head being pro-
vided with communicating bores, the said
bore terminating at the top of said slot and
said handle bore extending throughout the
length of the handle and through which the
nails or tacks are to be fed, said block hav-
100 ing an opening extending vertically through
the same and adapted to register with the
head bore when the same is slid to one posi-
tion within the slot, and means for detach-
ably securing one nail or tack to the head
105 directly beneath the block when the same is
in opposite position so that said nail or
tack may be driven into the work.

110 2. In a magazine hammer of the charac-
ter described, a handle, a head arranged
upon one end of the handle, a short slot in
one end of the head, a block slidable within
said slot, said handle and head being pro-
vided with communicating bores, the said
bore terminating at the top of said slot and
said handle bore extending throughout the
length of the handle and through which the
nails or tacks are to be fed, said block hav-
115 ing an opening extending vertically thru the
same and adapted to register with the head
bore when the same is slid to one position
within the slot, means for detachably secur-
ing one nail or tack to the head directly
120 beneath the block when the same is in op-
posite position so that said nail or tack may
125 be driven into the work.

130

be driven into the work, said securing means being of such a construction, as to shake loose from the tacks under the impact of the hammer against the work.

- 5 3. In a magazine hammer of the character described, a handle, a head arranged upon one end of the handle, a short slot in one end of the head, a block slideable within said slot, said handle and head being provided with communicating bores, the said bore terminating at the top of said slot and said handle bore extending throughout the length of the handle and thru which the nails or tacks are to be fed, said block having an opening extending vertically through the same and adapted to register with the head bore when the same is slid into one

position under the slot, means for detachably securing one nail or tack to the head directly beneath the block when the same is in opposite position so that said nail or tack may be driven into the work, said securing means being of such a construction, as to shake loose from the tacks under the impact of the hammer against the work, finger control means for moving the block to the last mentioned position, and automatic means for returning the block to the first-mentioned position, so that the catch within the communicating head and handle bores cannot pass forwardly therethrough.

In testimony whereof I affix my signature.

GEORGE PATTON.
